Primary Examiner — Eric L Goodman*Assistant Examiner* — Jennifer M Campbell(74) *Attorney, Agent, or Firm* — Rosenberg, Klein & Lee(57) **CLAIM**

The ornamental design for an ash receptacle, as shown and described.

DESCRIPTION

FIG. 1 is a front perspective view of an ash receptacle, showing my new design;

FIG. 2 is a right elevational view thereof, the left elevational view being a mirror image of the right elevational view;

FIG. 3 is a front elevational view thereof;

FIG. 4 is a bottom plan view thereof;

FIG. 5 is a top plan view thereof; and,

FIG. 6 is a rear elevational view thereof.

The broken lines shown in the figures are included for illustrating unclaimed portions of the ash receptacle and form no part of the claimed design.
